UNITED STATES PATENT OFFICE.

JOSEPH E. CRISP, OF BOSTON, AND GEORGE W. COPELAND, OF MALDEN,
MASSACHUSETTS.

MACHINE FOR LASTING BOOTS OR SHOES.

SPECIFICATION forming part of Letters Patent No. 329,367, dated October 27, 1885.

Application filed September 1, 1885. Serial No. 175,875. (No model.)

To all whom it may concern:

Be it known that we, JOSEPH E. CRISP, of Boston, Massachusetts, and GEORGE W. COPELAND, of Malden, in the county of Middlesex and Commonwealth of Massachusetts, both being citizens of the United States, have invented new and useful Improvements in Machines for Lasting Boots and Shoes; and we do hereby declare the following to be a full, clear, and exact description of the invention, reference being had to the accompanying drawings, forming a part of this specification, in explaining its nature, of which—

Figure 1 is a side elevation of our improved machine. Fig. 2 is a plan of the same. Fig. 3 is a section of Fig. 2, taken on line xx . Fig. 4 is a section of Fig. 2, taken on the center line. Fig. 5 is a plan with the upper parts and heel-support removed, showing the full operation of the toe-band. Fig. 6 is an end elevation with the heel-support removed.

The object of our invention is to produce a machine by which the toe portion of the upper of boots and shoes may be readily drawn and turned down upon the insole by the aid of manual power only in any part of the operation preparatory to fastening the same, and which will require no adjustments for different sizes of the same style of lasts.

It consists of improved heel-supporting devices which hold and carry the heel so that the toe portion of the shoe is firmly held at the proper angle with reference to the toe-lasting plates, and which, without regard to the length of the shoe, can be locked in position by a lever always moving through the same arc.

It consists, further, of an improved band of flexible material, preferably of leather or metal, for the purpose of securely holding the upper around the toe of the last, just below the lasting-plate, and operating from a point near or at the center of the toe, and while being drawn from such center toward and around the toe portion of the sides, and continuing by the strain it exerts upon succeeding portions of the upper which are subject to its action as it is caused to be drawn around the toe-upper to firmly hold the upper-leather against the last. As this band is drawn from the center of the toe to the sides of the last, it

will of course conform automatically to all shapes of lasts.

It consists, further, in improved means of changing the inclination of the boot or shoe, so as to promote the convenience of the operation.

In the drawings, A represents the body of the machine, which is carried and may be swung and secured at any desired angle by the stationary piece A', made fast to any suitable foundation. The top surface of this body is provided with slide-grooves A'', in which move the sliding bars A''. These sliding bars A'', as hereinafter described, operate the band for pressing the toe portion of the upper against and firmly around the last. On the top of body A move the lasting-plates C'. On one side of body A is secured the bracket A', which supports and carries the heel devices, Figs. 1, 2, and 4. The toe-lasting band b, Figs. 4, 5, and 6, preferably secured to body A, at b', is a piece of leather or other flexible material formed with an ear secured to body A, as shown. The upper part of the band, which is drawn around the toe, may be of any desired width, and its two ends are secured to the small blocks b'', which connect them with the sliding bars A'', by the connections b', so that pressure exerted upon bars A'' is communicated to the ends of band b, as can be clearly seen by reference to Fig. 5, and results in drawing the band against and around the toe of the last. A spring may be attached to this band b to keep it open so that the largest boot or shoe toe will freely pass to the center thereof without touching the ends of the band. Close above the upper edge of the band b is located the toe-downhold C, which prevents the surface of the upper when turned over upon the inner sole from being forced by the heel-supporting device above the line of action of the toe-lasting plates. These toe-lasting plates C' are connected to downhold C by and swing with the links C'' and C'', C'' being provided with suitable handles, C'. The length of the links C'' and C'' with reference to each other govern the motion of plates C' so that its ends next to downhold C move in coincident lines with the angular ends of C and prevent any portion of the upper from getting between downhold C and plates C'. The operating

ends of plates C' are held down to their work by the curved plate C⁵, secured to body A by screws, as shown. There are also formed on the handles C⁴, that form part of the links C³, devices for operating the sliding bars A³, so that upon the forward motion of the handles C⁴ the drawing of the band b commences, continues, is finished, and held in position before the lasting-plates begin to operate, and also 10 while these plates are turning and holding the upper over and down upon the insole. This is clearly shown in Figs. 2 and 3. By reference to Fig. 3 it will be seen that the bars A³ are formed of two parts, a and a', pressed 15 apart by the spring a², and held from being pressed too far apart by the rod a³ and pin a⁴. The connections b³ are pivoted to parts a' and a⁵, and at a⁶ on a' is pivoted a swinging link, c, Fig. 2. The other end of this link c is provided with a round bolt-head, c', below it, which, so long as it is desired to move a' forward, moves in the slide-grooves; but when part a' has reached the desired limit of forward motion bolt-head c' is swung into the half-round 20 cavity A⁸, Figs. 2, 3, and 5, and is there retained until the lasting-plates have been operated and returned back to the same position. During this operation the band b has been held against the upper with a force governed 25 by the strength of the spring a². To move and swing at the proper time link c, the body of its bolt is prolonged so as to reach far enough above link c to carry the roll c², and C⁴ is provided with a groove, C⁶, that engages 30 with the roll c², moves it forward until roll c² is opposite half-round cavity A⁸, when it, by reason of the change of angle C⁴, passes into cavity A⁸, and is there held by the curved part of C⁴ C⁷, and prevented from moving there- 35 from until C⁶ returns, when it passes back to its starting-point. This construction permits the band to be automatically drawn around a toe of any size, and also enables the operator to move either one or both sides of the band up 40 to and against the upper, as may be desired, before operating the lasting-plates.

The heel-supporting device holds the heel at the proper height with reference to the curve of that part of the toe operated upon by 45 the lasting-plates, and is constructed as follows: On the bracket A⁴, at A⁵, is pivoted the lever D, Figs. 1, 2, and 4. On lever D slides the half-round piece D', which can be ad- 50 justed and secured to lever D at any distance from the center by the set-screw D². The half-round piece D' carries on its top the heel-gage D⁴, against which the heel is raised be- 55 fore pressure is exerted upon it. To the ends of the half-round piece D' are attached the ends 60 of a sling, D³, preferably of leather, of any convenient width, which embraces or hugs the back or counter portion of the heel. The pin E, made fast in lever D, passing through bracket A⁴, acts as a pivot, and has securely 65 fastened to it the segmental ratchet F. Made fast under bracket A⁴ is the strong spring G,

provided at G' with the fixed pin G². Upon pin G² is pivoted the handle H and lever H', which may be made in one piece, provided with the stop-pin h. To the lever H' is connected the pawl H², provided with the stop-pin h'. The lever H' is so proportioned that the motion of the point of the pawl H² is somewhat more than the distance between the teeth of the ratchet F when the handle H is moved from stop h to stop h', and when the stop h' is pressed against G the end of pawl H² is raised above the teeth of the ratchet F, as shown by the dotted lines. To secure the boot or shoe by this apparatus, the handle H is pressed fully back and the ratchet F left free to swing with the lever D. The heel is passed into the sling and held up against the gage D⁴. The lever or arm D is then swung forward until the toe of the last is under the toe-downhold C and against the center of the band b. Then the handle H is moved down. The pawl H² drops into the tooth of ratchet F under it, and the full downward motion of handle H presses, holds, and locks the toe against the center of the band b and under downhold C with the desired force, which is communicated by the spring G. The band b and the lasting-plates are operated as before described. 85

It will be observed by reference to Fig. 2 that the leg portion of a boot can be passed 95 sidewise into the machine, instead of passing it downward, as is usual.

What we claim as new, and desire to secure by Letters Patent, is—

1. In a machine for lasting the toe part of boots and shoes, the combination, with toe-lasting mechanism, of the heel pressing and holding device, swinging on the arc of a circle, for the purpose of positioning and locking a last 105 with the upper thereon with reference to the toe-lasting mechanism, substantially as shown and described.

2. In a machine for lasting the toe part of boots and shoes, the combination of the swinging lever D, ratchet F, spring G, handle H, pawl H², and the stop-pins h and h', substantially as and for the purposes set forth.

3. In a machine for lasting the toe part of boots and shoes, the combination of the lever D, the sliding piece D', and gage D⁴, substantially as shown, and for the purposes set forth.

4. In a machine for lasting the toe part of boots and shoes, the combination of the lever D, the sliding piece D', gage D⁴, and sling D³, operating as described, and for the purposes set forth.

5. In a machine for lasting the toe portion of boots and shoes, a band, b, and mechanism, substantially as described, for pressing it against the median line of the toe and drawing it around the sides thereof, in the manner described, and for the purposes set forth.

6. In a machine for lasting the toe portions 130 of boots and shoes, the combination of the band b, block b², connections b³, slide-bars A³,

springs a^2 , rods a^3 , and pins a^4 , for the purposes set forth.

7. In a machine for lasting the toe portions of boots and shoes, the combination of the 5 slide-bars A^3 , the links c , bolt-heads c' , rolls c^2 , the base having half-round cavities A^X and grooves C^6 , and handles C^4 , provided with curves C^7 , for the purposes set forth.

8. In a machine for lasting the toe portions

of boots and shoes, the combination of the 10 handle C^4 , links C^3 C^2 , lasting-plates C' , toe-downhold C , and plate C^5 , all operating as described, substantially as set forth.
